US00D730911S

(12) **United States Design Patent**
Lim et al.

(10) **Patent No.:** US D730,911 S
(45) **Date of Patent:** ** Jun. 2, 2015

(54) **MEMORY CARD**

(71) Applicant: **SAMSUNG ELECTRONICS CO., LTD.**, Suwon-si (KR)

(72) Inventors: **Gwang-Man Lim**, Seoul (KR); **Il-Mok Kang**, Suwon-si (KR); **Seok-Jae Han**, Seoul (KR); **Sang-Chul Kang**, Hwaseong-si (KR); **Seok-Cheon Kwon**, Yongin-si (KR); **Seok-Chan Lee**, Hwaseong-si (KR)

(73) Assignee: **SAMSUNG ELECTRONICS CO., LTD.**, Suwon-si (KR)

(**) Term: **14 Years**

(21) Appl. No.: **29/507,479**

(22) Filed: **Oct. 28, 2014**

(30) **Foreign Application Priority Data**

May 2, 2014 (KR) 30-2014-0022338

(51) **LOC (10) Cl.** **14-02**

(52) **U.S. Cl.**

USPC **D14/436**

(58) **Field of Classification Search**

(57) **CLAIM**

The ornamental design for a memory card, as shown and described.

DESCRIPTION

FIG. 1 is the perspective view of the memory card showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a rear perspective view thereof.

Broken lines and entirely unshaded portions contained within broken line are not claimed. The dot dash lines in the figures represent an unclaimed boundary line and form no part of the claimed design.

1 Claim, 6 Drawing Sheets
